UNITED STATES PATENT OFFICE.

CHARLES G. W. NITZ, OF MILWAUKEE, WISCONSIN.

CANDY-PULLING MACHINE.

Application filed October 25, 1923. Serial No. 670,669.

To all whom it may concern:

Be it known that I, CHARLES G. W. NITZ, a citizen of the United States, residing at Milwaukee, in the county of Milwaukee and 5 State of Wisconsin, have invented new and useful Improvements in Candy-Pulling Machines, of which the following is a specification.

My invention has reference, in its broad 10 aspect, to improvements in that type of candy pulling machines exemplified by all floating pulling pins actuated to follow each other in a path contemplated by the figure 8, and arranged to relatively and alternately 15 intersect and align six times during a single cycle of operation, as defined in my patent #1,278,197, granted September 10th, 1918; and more particularly it is my purpose to incorporate in a single, compact and efficient 20 machine a plurality of all floating pulling pin units whereby to multiply the working capacity of the machine without proportionately increasing the number of parts of the machine, or the consumption of power to 25 operate it.

The concept embodied in my present invention includes, among other equally advantageous features which will be apparent as the description proceeds; first, a relatively 30 staggered arrangement of the pinning pins of the respective units to the end that the load is balanced, and circulation of air afforded; second, the provision of improved drums, each formed with novel, opposed operating or pin carrying heads whereby the 35 pins of the pulling units are caused to move simultaneously in paths having similar conformation; third, the employment of a unitary driving element for actuating the moving parts of the machine, and; fourth, the 40 provision of a novel, cast and machined, two part housing for supporting and retaining the separate parts of my device.

The particular elements of my candy pulling 45 machine employed to accomplish the objects attributed to it will be hereinafter more fully described in detail and specifically pointed out in the claims appended hereunto and forming a part of this specification.

In the accompanying drawings wherein is 50 illustrated the preferred embodiment, and one slight modification of my invention;—

Figure 1 is a perspective view of the assembly, with the top section of the housing 55 removed to show the arrangement of the interior elements thereof;

Figure 2 is a perspective view of the top section inverted to more clearly define its construction;

Figure 3 is a view contemplating a re-arrangement of the two pulling sides or units of my machine to show the relative disposition of the pulling pins of each at one stage in a cycle of operation, and also showing the construction and arrangement of the shifting member employed to transfer pins from one carrying head or disk to its coacting carrying head or disk;

Figure 4 is a sectional elevation through the assembly of my machine and taken from a position with respect to the pulling units contemplated by the line 4—4 of Figure 3;

Figure 5 is an elevation of a section of the housing utilized with a slightly modified form of my invention;

Figure 6 is a side view of the drum used with the modified form;

Figure 7 is an edge view of the drum used with the modified form;

Figure 8 is a side view of the drive gearing used with the modified form;

Figure 9 is an edge view of said drive gearing;

Figure 10 is a detail view of the pulling pins as formed and relatively arranged in my modified type of candy pulling machine, and;

Figure 11 is a diagrammatic view illustrative of the relative positions of the pulling pins of my invention at six different stages in a single cycle of operation.

Like characters of reference designate like or similar parts throughout the several views of the drawings, in which;—

The numeral (1) designates the lower section of my two part, cast housing, the upper section (2) of which is normally superposed thereupon and retained in place by bolts (3). The meeting face of each section is formed with coincident semi-cylindrical machined declivities (4) which register to receive the operating mechanism of my candy pulling machine. Formed integrally with and arranged centrally of each section of the housing and extending longitudinally thereof are a plurality of machine bearing members which are connected and supported by a web (5). The bearing members of each section are identical in construction and conformation and register to form the assembly. The identity and function of each of the said bearing

ing members will be defined in detail hereinafter. The lower section (1) is formed with legs (6) for supporting the machine upon a suitable base.

5   Mounted for rotation in the housing are drums (7) having identically formed heads (8) connected by hubs (9). The hubs (9) rotate in bearing blocks formed by registering bearing units (10) of the housing. The heads (8) of each drum (7) consist in circular facing members or plates (11), and gears (12). The gears (12) of one drum mesh with the gears (12) of the other so that the drums are caused to rotate simultaneously and oppositely. The facing plate and gear on each side of each drum are formed with three notches (13) disposed each at a point in the periphery of the facing plate and gear coincident with a third 10 of the circumference. The notches on each side of each drum are staggered with respect to each other, and in the assembly the notches on each side of each drum register with the notches on the corresponding side of the adjacent drum consecutively as the drums are rotated. The portions of the sections of the housing receiving the facing plates (11) and gears (12) are machined to provide loose bearing surfaces (14) and 15 (15) respectively.

30   In carrying into effect the concept of my present invention I employ six pulling pins (16)—three for each side or pulling unit of the machine. The pins (16) are designed to be loosely carried in certain of the notches (13) in the heads (8), with the hubs (17) thereof slidably engaging the annular ribs (18) in the housing and the short or inner end of the pins moving in the track (20) formed between the ribs (18). The pins carried by each side or pulling unit of the machine are relatively staggered so that a fine balance is maintained of the load carried by them, and as there are but three pins for each six notches, and as such notches are relatively staggered with respect to each side of the machine, air circulation is permitted with corresponding increase in working efficiency.

50   As defined in my Patent #1,278,197 granted September 10th, 1918, the pins contemplated by my present invention are all floating, and are transferable alternately between adjacent heads (8) to move in a path defined by the figure 8. The shifters employed to accomplish this result are the same as those described in my above mentioned patent, and each consists in a head (21) curved lateral arms (22) and a detent (23). Each shifter rocks upon a stud (24) and is limited in movement by the engagement of a fixed stop pin (25) with the end walls of a slot (26) in the head (21) of the shifter.

65   In Figure 3 an aligned, or major posi-

tion of the pins on one side of my machine is shown at A, while the corresponding position of the pins on the opposite side is shown at B. As is manifest, when the pins on one side are aligned the pins on the other side are disaligned, or in an intermediate position, due to the staggered relation of the notches (13). When the shifter is in the position shown at A the adjacent pin is in process of being transferred from one head to the other through contact of the detent (23) with the hub (17) of the pin, but as the pin is carried down by rotation of the heads its hub (17) strikes the arm (22) of the shifter intercepting its path of travel and throws the shifter to intercept a pin carried by the same head and transfer it to the other head—this position of the shifter and the respective pins is defined at B, which, although it is illustrative of the other side of the machine, is representative of the movement defined. It will be noted that no springs, or the like, are used to accomplish the desired result.

Referring now to Figure 11, six positions 90 of the pins of one pulling unit—one side of the machine—are shown. The diagram designated by A shows the pins at the commencement of a cycle; the next stage B shows the pin 2 as about to intersect the contemplated line between pins 1 and 3, and the pins again aligned at a different angle. At C the pin 3 is about to intersect the line between pins 1 and 2, and at D the pin 2 is about to intersect the line between pins 100 1 and 3. The intermediate positions of the pins are not illustrated diagrammatically, but are suggested by the view B of Figure 3. In diagrams E and F the pins 1 and 3 are about to intersect the lines between pins 105 2 and 3 and 1 and 2 respectively, thus completing a cycle of operation. It is manifest therefore, that each pin intersects an alignment of the others twice during a single cycle of operation, and that all the pins 110 align themselves six times during the cycle. Candy operated upon by my machine is thus subjected to twelve major pulling actions of the pins during a single cycle of operation of each pulling unit of the machine, as distinguished from a considerably less number of major pulling actions executed by machines having one or more fixed pins, or those having movable pins carried by rotating arms.

115   The actuating mechanism of my candy pulling machine comprises a transverse shaft (27) hung across an opening in the lower section (1) of the housing, and upon which are keyed gears (28) which mesh with the gears (12) of one of the drums. A drive gear (29) is also keyed to the shaft (27) which is operatively connected with a suitably source of power (not shown). Thus, the respective drums (7), being 120

125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

geared together, are rotated simultaneously and oppositely through the intermeshing of the gears (12) of one of the drums with the gears (28) on shaft (27) to cause the pins 5 to travel over a path defined by the figure 8 in the manner hereinbefore described. It will be noted that the machined bearing surfaces (14) of the housing confine the pins (16) in the proper notches until they reach 10 a neutral point when pins are transferred by the shifter from one drum to the other.

In the modified form of my present invention, illustrated in Figures 5 to 10 inclusive, both the housing and operating mechanism 15 are simplified, in that the machined web supported bearing members are dispensed with, and the drums (30) are rotatably mounted and supported directly by the housing (31), which has an annularly 20 flanged portion (32) extending into the coincident circular openings (33) therein which serves both to retain the drums in place and provide a machine bearing surface for the face plates of the drums. The drums in this 25 form of my invention are provided with relatively short hub portions (34); the space thus afforded between adjacent gears (35) serving to confine the hubs (36) of the pulling pins (37) shown in detail in Figure 10. 30 The drive mechanism for this form of my invention consists in a unit comprising two large gears (38) which mesh with gears (35), and an intermediate small drive gear (39). The unit as a whole is mounted in a 35 vertically extending opening between the housing sections formed by registering recesses (40) therein. Suitable openings (41) are provided in the walls of the recesses for journalling the pins (42) formed on the drive unit. Shifting means (not shown) for 40 transferring the pins (37) from one drum to the other are employed, which same may be of the nature of the shifting means defined in connection with the principal embodiment of my invention.

While the manner of operating my candy pulling machine is believed to be evident from the foregoing description, it is desired 50 to emphasize the attributes of simplicity and balance attained by the construction defined. The load represented by a batch of candy upon the pins of both pulling units is so distributed that a fine balance is maintained, and sufficient circulation of air permitted to insure maximum efficiency. Furthermore the peculiar construction and arrangement of the housing with respect to the operating parts of the machine provides 55 for a relatively high capacity for work with but slight increase of parts over the candy pulling machine defined by my Patent #1,278,197 granted September 10th, 1918.

While in the foregoing, there has been 60 illustrated and described such combination and arrangement of elements as constitute

the preferred embodiments of my invention, it is nevertheless desired to further emphasize the fact that interpretation of the invention should only be conclusive when made in the light of the subjoined claims. 70

Having described my invention and its objects with such attention to detail as will thoroughly acquaint one skilled in the art with its construction and advantages, I 75 claim:

1. A device of the character described comprising a plurality of pulling units consisting each in a plurality of floating members arranged to follow each other about a path approximating the figure 8, and aligning six times during a single cycle of operation, and each floating member intersecting the path of the others twice during a single cycle of operation, and the floating members of the respective pulling units being offset or staggered with respect to each other for the purpose defined. 80

2. A pulling device comprising a pair of rotatable members, a plurality of floating pulling members carried by the rotatable members and arranged to operate in units, the floating members of each unit being relatively staggered with respect to those of the other unit, and the floating members of all of the units being transferable between the rotatable members to move in paths approximating the figure 8. 90

3. A candy pulling machine comprising a housing formed with two sections, each section having integrally formed thereon bearing elements, the said bearing elements being adapted to register in assembly, a plurality of rotatable members mounted in the bearing members, and a plurality of floating members carried by the rotatable members and movable to travel in paths approximating the figure 8. 100

4. A candy pulling machine comprising a housing, a plurality of rotatable members carried by the housing and each formed with a plurality of notches, a plurality of floating members receivable in said notches, said floating members being divided into units, and means for transferring the respective floating members of one unit from one rotatable member to the other at a predetermined time and in alternation with the pins of the other unit for the purpose defined. 110

5. A candy pulling machine formed with a plurality of candy pulling units, each unit comprising a plurality of floating members arranged to follow each other about a path approximating the figure 8, and the floating members of each unit being staggered transversely with respect to the floating members of the other unit. 120

6. A device of the character described comprising a housing formed with a plurality of substantially horizontal bearing 130

elements, rotatable members supported by said bearing elements, and a plurality of floating candy pulling members carried by the rotatable elements and extending axially from each end thereof, said floating members being transferable between said rotatable members to move in paths approximating the figure 8.

7. A candy pulling machine comprising a housing carrying drums which are substantially horizontally and revolvably mounted side by side, each of said drums formed with notched heads, the notches in adjacent

heads at one end of the housing being in staggered relation to the notches in the heads at the other side of the housing, floating candy pulling members carried in the notches, means for transferring the floating members from one drum to the other at predetermined times, and means for rotating the drums simultaneously in opposite directions.

In testimony whereof, I affix my signature hereto.

CHARLES G. W. NITZ.
